REFRIGERATING APPARATUS

Ralph K. Miller, Dayton, Ohio, assignor to General Motors Corporation, Dayton, Ohio, a corporation of Delaware

Application July 19, 1934, Serial No. 736,010
Renewed October 8, 1935

14 Claims. (Cl. 62—126)

This invention relates to refrigerating apparatus and particularly to cooling elements or evaporators of such apparatus. In mounting an evaporator within a food storage compartment, of a refrigerator cabinet to be cooled, in the top central portion of the compartment and constructing the evaporator so that refrigerant is directed from a liquid refrigerant inlet connection directly through a refrigerated shelf or through a plurality of shelves prior to being circulated or distributed to the walls of the evaporator it has been found that bottled beverages placed adjacent the walls of the evaporator in the upper portion of a food storage compartment are not quickly or efficiently cooled to the proper low temperature. This difficulty arises from the fact that refrigerant passing through passages in the side walls of the evaporator has already completely evaporated or has absorbed all the heat it is capable of absorbing and is therefore incapable of absorbing additional heat at the upper portion or at the top of the side walls of the evaporator. This therefore inherently results in the presence of a warm pocket or a portion adjacent the top of the food compartment which is of a higher temperature than other portions of the compartment and into which the bottles extend. It is this difficulty that the present invention purports to overcome to produce an efficient evaporator and consequently efficient refrigeration or uniform cooling of all portions of a food storage compartment.

An object of my invention is to provide a sheet metal evaporator construction having, between the liquid refrigerant inlet and a refrigerant outlet connections thereof, an improved refrigerant flow circuit including a portion or duct connected in series with the inlet connection and another portion including a plurality of interconnected passages connected in parallel circuit relation with the refrigerant outlet connection.

In carrying out the foregoing object, it is a further object of my invention to form one extended portion and at least a part of the other portion of the refrigerant flow circuit, through the evaporator, between sheet metal portions bent to provide walls of a freezing chamber and to utilize one portion of the refrigerant flow circuit, connected in series with the refrigerant inlet connection, as an extended low temperature refrigerated wall portion at the top and across substantially the depth of the evaporator and another portion thereof as a sharp freezing zone or refrigerated shelf and to utilize the passages

of the other circuit, connected in parallel circuit relation with the refrigerant outlet connection, as a refrigerant distributing portion or cooling zone for the evaporator.

Further objects and advantages of the present invention will be apparent from the following description, reference being had to the accompanying drawings, wherein a preferred form of the present invention is clearly shown.

In the drawings:

Fig. 1 discloses a refrigerator cabinet with the access door to the food storage compartment thereof in open position and showing an evaporator constructed according to the present invention installed therein;

Fig. 2 is an enlarged front view of my improved evaporator showing a plurality of compartments formed therein by refrigerated shelves;

Fig. 3 is an elevational view of the left side of the evaporator shown in Fig. 2;

Fig. 4 is a fragmentary elevational view of the right side of the evaporator shown in Fig. 2;

Fig. 5 is a view of the bottom of the evaporator;

Fig. 6 is a fragmentary sectional view through the evaporator taken on line 6—6 of Fig. 4; and

Fig. 7 is a top view of the evaporator showing a plan view of one of the refrigerated shelves located within the freezing chamber of the evaporator.

For the purpose of illustration, I have shown in Fig. 1 of the drawings, an evaporator 20 constructed according to my invention mounted in a refrigerator cabinet 21 of any suitable construction or design. Preferably the cabinet comprises an insulated food storage compartment 22 having a door 23 providing access thereto and a machine compartment (not shown) disposed below the compartment 22. The refrigerant liquefying unit, of the refrigerating system connected with the evaporator 20, may be of any suitable type and is adapted to be mounted in the machine compartment disposed below the food storage compartment. Mechanical refrigerating apparatus of the type herein mentioned are well known to those familiar with the art and therefore need no further description.

My invention is directed to a finished evaporator which is produced by uniting, in any suitable manner, superimposed sheet metal portions or plates 25 and 26 (see Fig. 6) to produce a double walled structure having refrigerant passages formed between the sheet metal portions or plates. The double walled structure, formed

- by uniting the plates 25 and 26 is bent after securing the plates together to form a plurality of side walls 27 and 28 and a bottom wall 29 of an elongated horizontally disposed freezing chamber, 5
- 5 A liquid refrigerant inlet connection 31 and a gaseous refrigerant outlet connection or pipe 32 are connected to the evaporator 20 and communicate with the space or passage between the sheets or plates 25 and 26 of the double walled 10 member. Refrigerant inlet connection 31 is connected with a refrigerant flow control device or expansion valve 33 of any conventional or well-known design and the device or valve 33 governs the flow of refrigerant to the evaporator in any 15 well-known manner. In order to extend a portion of the series refrigerant flow circuit through one or more of the walls 27 and 28 of the evaporator 20 to precool the air cooling walls or to rapidly reduce the temperature at the top thereof, a refrigerant conveying duct 35 is formed by 20 and located between the sheet metal members 25 and 26 on the upper left hand side of the evaporator or wall 27. The refrigerant duct 35 communicates with the liquid refrigerant inlet connection or pipe 31 at the rear of the evaporator 25 and the duct extends horizontally across substantially the width of the side wall. The duct 35 has a reverse turn 36 provided near the front portion of the evaporator so as to form a loop and 30 permit the tail end of the duct 35 to extend back towards the rear of the evaporator (see Fig. 3). The outlet or tail end of duct 35 is connected with a pipe 37 (see Figs. 2, 3, and 7) which pipe extends across the top of the freezing chamber and 35 connects with a second refrigerant conveying duct 38 formed by and located between the sheet metal members or plates 25 and 26 on the upper right hand side of the evaporator or along the wall 28 thereof. The duct 38 extends horizontally across 40 substantially the width of the side wall and communicates with an outlet pipe 39 at the rear of the evaporator 20. Duct 38 has a reverse turn 40 provided near the front of the evaporator so as to form a loop and permit the tail end of the duct 45 38 to extend toward the back of the evaporator (see Fig. 4). The pipe 39 connected with the outlet end of duct 38 extends downwardly to a refrigerated shelf.

In order to provide a freezing portion and a 50 refrigerant distributing or air cooling portion for the evaporator the refrigerant flow circuit includes a means in the form of a horizontally disposed shelf or shelves 41 and 42 respectively which divide the interior of the freezing chamber, 55 formed by the walls 27, 28 and 29 of the evaporator, into a plurality of superimposed compartments. Each of the shelf means 41 and 42 comprises two superimposed sheet metal plates or members 43 and 44 (see Fig. 6) secured together 60 in any suitable manner. The lower of the plates or members 44 of shelves 41 and 42 have formed therein depressions which, when the plates 43 and 44 are secured together, provide a serpentine refrigerant passage or duct 45 extending horizontally 65 through the chamber. The refrigerant duct 45 in shelf 41 has its inlet communicating with the pipe 39 and has its outlet communicating with a pipe 47 which connects with the inlet to duct 45 provided in shelf 42. A pipe 48 connects 70 the outlet of duct 45, in shelf 42, with a refrigerant distributing header or manifold passage 51 formed by and located between the sheet metal plates or members 25 and 26 in the bottom wall 29 of the evaporator 20 (see Fig. 5). A plurality 75 of refrigerant conveying conduits 53 are formed

by and located between the plates 25 and 26 and are connected in multiple with the header or manifold passage 51 and extend around at least a portion of the bottom wall 29 and upwardly over a portion of the side wall 27 of the evaporator 5. A second set of a plurality of refrigerant conduits 54 are formed by and located between the sheet metal members 25 and 26 and are connected in multiple with the header or manifold passage 51 and extend around at least a portion 10 of the bottom wall 29 and upwardly over a portion of the side wall 28 of the evaporator. Both sets of the plurality of refrigerant conduits 53 and 54 communicate with one or more headers or manifold passages 55 formed by and located between the plates 25 and 26 in the side walls 27 and 28 of the evaporator. One of each of the headers 55 located on opposite side walls of the evaporator and preferably the top header has a pipe 56 connecting the headers or manifold passages 53 and 54 with the outlet pipe 32.

The refrigerated shelves 41 and 42 may be secured to the side walls 27 and 28 of the evaporator 20 in any suitable manner and the evaporator together with these shelves and the pipe connections may be coated or plated with any suitable material, for example, they may be chromium plated. Any suitable bracket or mounting means may be provided for mounting the evaporator 20 in the food storage compartment 22 of the cabinet 30 21. It is to be understood that the foregoing defined refrigerant conveying ducts, conduits, passages, or header manifolds are sealed about their edges by uniting the metal members 25 and 26 together adjacently thereto.

From the above description of the refrigerant conveying ducts, conduits, passages or header manifolds it may be seen that I have provided a refrigerant flow circuit through the sheet metal evaporator 20, between the liquid refrigerant inlet 40 and the refrigerant outlet connections 31 and 32 thereof, which includes an extended portion communicating in series with the liquid refrigerant inlet connection 31 and another portion communicating in multiple or in parallel circuit 45 relation with the outlet connection 32 and that I have extended a portion of the series flow circuit through the walls of the evaporator so as to circulate refrigerant directly from the flow control device or expansion valve 33 through a 50 portion of these walls prior to circulating the refrigerant to the refrigerated shelves. More fully explaining this refrigerant flow circuit, between the refrigerant inlet and outlet connections 31 and 32 of the evaporator, the portions 55 connected in series with the refrigerant inlet connection 31 includes the refrigerant duct 35, pipe 37, duct 38, pipe 39, conduit 43 formed in shelf 41, pipe 47, conduit 45 formed in shelf 42, and a pipe 48 which leads to the lower distributing header or manifold passage 51. The portion 60 of the refrigerant flow circuit communicating in parallel circuit relation with the outlet connection 32 of the evaporator includes the distributing header or manifold passage 51, the refrigerant conduits 53 and 54 and the headers or manifolds 55.

Since refrigerant is first circulated from the inlet pipe 31 through the refrigerant ducts 35 70 and 38 these ducts and the portions of the plates 25 and 26 immediately surrounding the ducts provide a very cold zone in the top portion of the walls of the evaporator and thus prevent the formation of warm pockets or pockets of 75

a temperature higher than other localities within the food storage compartment 22. Thus bottled beverages will be quickly and efficiently cooled when placed in an upright or vertical position 5 adjacent walls of my improved evaporator. The refrigerant after passing through the refrigerant ducts 35 and 38 is, as before stated, directed to the refrigerant passage 45 in the upper shelf 41 and thence to the refrigerant passage 45 in the lower shelf 42. The shelves 41 and 42 thus provide fast freezing supports or zones for ice trays or the like 58 (see Fig. 1) adapted to contain substances to be frozen. Also since refrigerant is circulated in a series path to the bottom wall 15 29 of the evaporator this bottom wall provides a support for a tray or receptacle for rapidly chilling desserts and the like. The multiple flow of refrigerant or parallel circuit flow through conduits 53 and 54 provide refrigerated walls for 20 the evaporator which cool and cause circulation of air within the food storage compartment 22 of the refrigerator cabinet 21.

From the foregoing it will become apparent that I have provided a novel sheet metal evaporator having an improved and an efficient refrigerant flow circuit incorporated therein, between the liquid refrigerant inlet connection and the refrigerant outlet connection thereto, which uniformly cools all portions of the interior of a food 30 storage compartment to approximately the same temperature, thus preventing the formation of warm pockets and at the same time provides a quick freezing or fast freezing zone and another portion provides the evaporator with air cooling 35 wall zones. My improved evaporator is not only very efficient during the process of producing refrigeration but is also very efficient for effecting quick and uniform defrosting of the walls thereof.

While the form of embodiment of the invention as herein disclosed, constitutes a preferred form, it is to be understood that other forms might be adopted, all coming within the scope of the claims which follow.

What is claimed is as follows:

45 1. An evaporator comprising superimposed sheet metal portions secured together and bent to provide a plurality of walls of a freezing chamber, a refrigerant conveying duct extending in a horizontal direction substantially across the upper part of a certain wall of said chamber and having a refrigerant inlet connection, a header or manifold passage disposed below said refrigerant duct and extending in a direction substantially parallel thereto along a certain wall 50 of said chamber, means for connecting said duct with said header or manifold passage, a plurality of refrigerant conveying conduits communicating with said header or manifold passage, said refrigerant duct, said header or manifold passage and said refrigerant conduits being formed by and located between the sheet metal portions of the chamber walls, and said duct, said header or manifold and the connecting means therebetween together with said conduits being arranged 55 to provide a refrigerant flow circuit through said evaporator including an extended portion in series with said inlet connection and another extended portion comprising said conduits connected in parallel circuit relation with each other and having a common outlet connection.

70 2. An evaporator comprising superimposed sheet metal portions secured together and bent to provide a plurality of walls of a freezing chamber, a refrigerant conveying duct extending in a horizontal direction substantially across the

upper part of a certain wall of said chamber and having a refrigerant inlet connection, a header or manifold passage disposed below said refrigerant duct and extending in a direction substantially parallel thereto along a certain wall of 5 said chamber, means for connecting said duct with said header or manifold passage, a plurality of refrigerant conveying conduits communicating with said header or manifold passage, said refrigerant duct, said header or manifold 10 passage and said refrigerant conduits being formed by and located between the sheet metal portions of the chamber walls, and said duct, said header or manifold and the connecting means therebetween together with said conduits 15 being arranged to provide a refrigerant flow circuit through said evaporator including an extended portion in series with said inlet connection and another extended portion comprising said conduits connected in parallel circuit relation with each other and having a common outlet connection, said connecting means between said duct and said header or manifold passage including a refrigerated shelf or shelves disposed within said freezing chamber for receiving and 20 supporting thereon a receptacle adapted to contain a substance to be congealed or frozen.

3. An evaporator comprising superimposed sheet metal portions secured together and bent to provide a vertical wall and a horizontal bottom wall of a freezing chamber, a refrigerant conveying duct extending in a horizontal direction substantially across the upper part of the vertical wall of said chamber and having a refrigerant inlet connection, a header or manifold 30 passage extending in a direction substantially parallel to said refrigerant duct along the bottom wall of said chamber, means for connecting said duct with said header or manifold passage, a plurality of refrigerant conveying conduits 35 communicating with said header or manifold passage, said refrigerant duct, said header or manifold passage and said refrigerant conduits being formed by and located between the sheet metal portions of the chamber walls, and said duct, said header or manifold passage and the connecting means therebetween together with said conduits being arranged to provide a refrigerant flow circuit through said evaporator including an extended portion in series with said inlet 40 connection and another extended portion comprising said conduits connected in parallel circuit relation with each other and having a common outlet connection.

4. An evaporator comprising superimposed sheet metal portions secured together and bent to provide a vertical wall and a horizontal bottom wall of a freezing chamber, a refrigerant conveying duct extending in a horizontal direction substantially across the upper part of the vertical wall of said chamber and having a refrigerant inlet connection, a header or manifold passage extending in a direction substantially parallel to said refrigerant duct along the bottom wall of said chamber, means for connecting said duct with said header or manifold passage, a plurality of refrigerant conveying conduits 55 communicating with said header or manifold passage, said refrigerant duct, said header or manifold passage and said refrigerant conduits being formed by and located between the sheet metal portions of the chamber walls, and said duct, said header or manifold passage and the connecting means therebetween together with said conduits being arranged to provide a refrigerant flow circuit 60

through said evaporator including an extended portion in series with said inlet connection and another extended portion comprising said conduits connected in parallel circuit relation with each other and having a common outlet connection, said connecting means between said duct and said header or manifold passage including a refrigerated shelf or shelves disposed within said freezing chamber for receiving and supporting thereon a receptacle adapted to contain a substance to be congealed or frozen.

5. An evaporator comprising superimposed sheet metal portions secured together and bent to provide a vertical wall and a horizontal bottom wall of a freezing chamber, a refrigerant conveying duct extending in a horizontal direction substantially across the upper part of the vertical wall of said chamber and having a refrigerant inlet connection, a header or manifold passage extending in a direction substantially parallel to said refrigerant duct along the bottom wall of said chamber, means for connecting said duct with said header or manifold passage, a plurality of refrigerant conveying conduits communicating with said header or manifold passage and traversing a portion of the bottom and of the vertical wall of said chamber, said refrigerant duct, said header or manifold passage and refrigerant conduits all being formed by and located between the sheet metal portions of the chamber walls, and said duct, said header or manifold passage and the connecting means therebetween together with said conduits being arranged to provide a refrigerant flow circuit through said evaporator including an extended portion comprising said conduits connected in series with said inlet connection and another extended portion in parallel circuit relation with each other and having a common outlet connection.

40. 6. An evaporator comprising superimposed sheet metal portions secured together and bent to provide two upright walls and a bottom wall of a freezing chamber, a refrigerant conveying duct extending substantially across the upper part of one of said upright chamber walls in a substantially horizontal direction and having a refrigerant inlet connection and a refrigerant outlet, a second refrigerant conveying duct extending substantially across the upper part of the other of said upright chamber walls in a substantially horizontal direction and having a refrigerant inlet and a refrigerant outlet, means for connecting the refrigerant outlet of said first named refrigerant duct with the refrigerant inlet of said second named refrigerant duct, a header or manifold passage extending in a direction substantially parallel to said refrigerant ducts along the bottom wall of said chamber, means for connecting the refrigerant outlet of said second named refrigerant duct with said header or manifold passage, a plurality of refrigerant conveying conduits communicating with said header or manifold passage, said refrigerant ducts, said header or manifold passage and said refrigerant conduits being formed by and located between the sheet metal portions of the chamber walls, and said ducts together with the connecting means therebetween, said header or manifold passage together with the means connecting same with said last named duct and said conduits being arranged to provide a refrigerant flow circuit through said evaporator including an extended portion in series with said inlet connection to said first named duct and another extended portion comprising said conduits connected in parallel circuit relation with each other and having a common outlet connection, said connecting means between said second named refrigerant duct and said header or manifold passage comprising a refrigerated shelf or shelves disposed within said freezing chamber for receiving and supporting thereon a receptacle adapted to contain a substance to be congealed or frozen.

another extended portion comprising said conduits connected in parallel circuit relation with each other and having a common outlet connection.

7. An evaporator comprising superimposed sheet metal portions secured together and bent to provide two upright walls and a bottom wall of a freezing chamber, a refrigerant conveying duct extending substantially across the upper part of one of said upright chamber walls in a substantially horizontal direction and having a refrigerant inlet connection and a refrigerant outlet, a second refrigerant conveying duct extending substantially across the upper part of the other of said upright chamber walls in a substantially horizontal direction and having a refrigerant inlet and a refrigerant outlet, means for connecting the refrigerant outlet of said first named refrigerant duct with the refrigerant inlet of said second named refrigerant duct, a header or manifold passage extending in a direction substantially parallel to said refrigerant ducts along the bottom wall of said chamber, means for connecting the refrigerant outlet of said second named refrigerant duct with said header or manifold passage, a plurality of refrigerant conveying conduits communicating with said header or manifold passage, said refrigerant ducts, said header or manifold passage and said refrigerant conduits being formed by and located between the sheet metal portions of the chamber walls, and said ducts together with the connecting means therebetween, said header or manifold passage together with the means connecting same with said last named duct and said conduits being arranged to provide a refrigerant flow circuit through said evaporator including an extended portion in series with said inlet connection to said first named duct and another extended portion comprising said conduits connected in parallel circuit relation with each other and having a common outlet connection, said connecting means between said second named refrigerant duct and said header or manifold passage comprising a refrigerated shelf or shelves disposed within said freezing chamber for receiving and supporting thereon a receptacle adapted to contain a substance to be congealed or frozen.

8. An evaporator comprising sheet metal portions secured together and arranged to provide opposed upright walls of a freezing chamber, a single refrigerant duct having a portion thereof extending across one of the opposed freezing chamber walls and having another portion thereof extending across the other of said opposed freezing chamber walls, said duct having an inlet connection in the upper part of said one of said opposed upright freezing chamber walls, said duct being arranged to convey refrigerant from said inlet connection continuously in an undivided path first across said one of said opposed upright freezing chamber walls and thence across said other of said opposed upright walls, a header or manifold passage disposed below the inlet connection to said duct and extending along a certain wall of said chamber and having a connection with said single duct, a plurality of refrigerant conveying conduits communicating with said header or manifold passage, said header or manifold passage, said refrigerant conduits and at least said portions of said single continuous refrigerant duct being formed by and located between the sheet metal portions of the chamber walls, and said single continuous duct, said head-

- er or manifold passage and said conduits being arranged to provide a refrigerant flow circuit through said evaporator including an extended portion in series with said inlet connection and another extended portion comprising said conduits connected in parallel circuit relation with each other and having a common outlet connection, a portion of said single continuous duct including a refrigerated sharp freezing shelf for receiving and supporting thereon a receptacle adapted to contain a substance to be congealed or frozen.

9. An evaporator comprising superimposed sheet metal portions secured together and bent to provide a plurality of walls of a freezing chamber, a refrigerant conveying duct extending in a horizontal direction substantially across the upper part of a certain wall of said chamber and having a refrigerant inlet connection, a header or manifold passage disposed below said refrigerant duct and extending in a direction substantially parallel thereto along a certain wall of said chamber, means for connecting said duct with said header or manifold passage, a second header or manifold passage disposed below said refrigerant duct and above said first named header or manifold passage and extending in a direction substantially parallel to said refrigerant duct and said first named header or manifold passage along a certain wall of said chamber and having an outlet connection, a plurality of refrigerant conveying conduits extending between and communicating with each of said headers or manifolds, said refrigerant duct, said headers or manifolds, said refrigerant conduits being formed by and located between the sheet metal portions of the chamber walls, and said duct, said headers or manifolds and the conduits therebetween together with the means connecting the duct with said first named header or manifold being arranged to provide a refrigerant flow circuit through said evaporator including an extended portion in series with said inlet connection and another extended portion comprising said conduits connected in parallel circuit relation with each other by said headers or manifold passages and communicating with said outlet connection.

10. An evaporator comprising superimposed sheet metal portions secured together and bent to provide a plurality of walls of a freezing chamber, a refrigerant conveying duct extending in a horizontal direction substantially across the upper part of a certain wall of said chamber and having a refrigerant inlet connection, a header or manifold passage disposed below said refrigerant duct and extending in a direction substantially parallel thereto along a certain wall of said chamber, means for connecting said duct with said header or manifold passage, a second header or manifold passage disposed below said refrigerant duct and above said first named header or manifold passage and extending in a direction substantially parallel to said refrigerant duct and said first named header or manifold passage along a certain wall of said chamber and having an outlet connection, a plurality of refrigerant conveying conduits extending between and communicating with each of said headers or manifolds, said refrigerant duct, said headers or manifolds and the conduits therebetween together with the means connecting the duct with said first named header or manifold being arranged to provide a refrigerant flow circuit through said evaporator including an extended portion in series with said inlet connection and another extended portion comprising said conduits connected in parallel circuit relation with each other by said headers or manifold passages and communicating with said outlet connection.

11. An evaporator comprising superimposed sheet metal portions secured together and bent to provide a vertical wall and a horizontal bottom wall of a freezing chamber, a refrigerant conveying duct extending in a horizontal direction substantially across the upper part of the vertical wall of said chamber and having a refrigerant inlet connection, a header or manifold passage extending in a direction substantially parallel to said refrigerant duct along the bottom wall of said chamber, means for connecting said duct with said header or manifold passage, a second header or manifold passage disposed below said refrigerant duct and extending in a direction substantially parallel to said refrigerant duct and having an outlet connection, a plurality of refrigerant conveying conduits extending between and communicating with each of said headers or manifolds, said refrigerant duct, said headers or manifolds and the conduits therebetween together with the means connecting the duct with said first named header or manifold being arranged to provide a refrigerant flow circuit through said evaporator including an extended portion in series with said inlet connection and another extended portion comprising said conduits connected in parallel circuit relation with each other by said headers or manifold passages and communicating with said outlet connection.

12. An evaporator comprising superimposed sheet metal portions secured together and bent to provide a vertical wall and a horizontal bottom wall of a freezing chamber, a refrigerant conveying duct extending in a horizontal direction substantially across the upper part of the vertical wall of said chamber and having a refrigerant inlet connection, a header or manifold passage extending in a direction substantially parallel to said refrigerant duct along the bottom wall of said chamber, means for connecting said duct with said header or manifold passage, a second header or manifold passage disposed below said refrigerant duct and extending in a direction substantially parallel to said refrigerant duct and having an outlet connection, a plurality of refrigerant conveying conduits extending between and communicating with each of said headers or manifolds, said refrigerant duct, said headers or manifolds and the conduits therebetween together with the means connecting the duct with said first named header or manifold being arranged to provide a refrigerant flow circuit through said evaporator including an extended portion in series with said inlet connection and another extended portion comprising said conduits connected in parallel circuit relation with each other by said headers or manifold passages and communicating with said outlet connection.

connecting the duct with said first named header or manifold being arranged to provide a refrigerant flow circuit through said evaporator including an extended portion in series with said inlet connection and another extended portion comprising said conduits connected in parallel circuit relation with each other by said headers or manifold passages and communicating with said outlet connection, said connecting means between 5 said duct and said first named header or manifold passage including a refrigerated shelf or shelves disposed within said freezing chamber for receiving and supporting thereon a receptacle adapted to contain a substance to be congealed or frozen.

10 15. 13. An evaporator comprising superimposed sheet metal portions secured together and bent to provide two upright walls and a bottom wall of a freezing chamber, a refrigerant conveying duct extending substantially across the upper part 20 of one of said upright chamber walls in a substantially horizontal direction and having a refrigerant inlet connection and a refrigerant outlet, a second refrigerant conveying duct extending substantially across the upper part of the 25 other of said upright chamber walls in a substantially horizontal direction and having a refrigerant inlet and a refrigerant outlet, means for connecting the refrigerant outlet of said first named refrigerant duct with the refrigerant inlet 30 of said second named refrigerant duct, a header or manifold passage extending in a direction substantially parallel to said refrigerant ducts along the bottom wall of said chamber, means for connecting the refrigerant outlet of said second 35 named refrigerant duct with said header or manifold passage, a second header or manifold passage extending in a direction substantially parallel to said refrigerant ducts and to said first named header or manifold passage along one of 40 the upright walls of said chamber, a plurality of refrigerant conveying conduits extending between and communicating with both of said headers or manifold passages, an outlet connection for said second named header or manifold passage, 45 said refrigerant ducts, said headers or manifold passages and said refrigerant conduits being formed by and located between the sheet metal portions of the chamber walls, and said ducts together with the connecting means therebetween, said headers or manifold passages together with the means connecting the first named header or manifold passage with said last named duct and said conduits being arranged to provide a refrigerant flow circuit through said evaporator 50 including an extended portion in series with said inlet connection to said first named duct and another extended portion comprising said conduits connected in parallel circuit relation with each 55

other by said headers or manifold passages and communicating with the outlet connection of said second named header or manifold passage.

14. An evaporator comprising superimposed sheet metal portions secured together and bent to provide two upright walls and a bottom wall of a freezing chamber, a refrigerant conveying duct extending substantially across the upper part 5 of one of said upright chamber walls in a substantially horizontal direction and having a refrigerant inlet connection and a refrigerant outlet, a second refrigerant conveying duct extending substantially across the upper part of the other of said upright chamber walls in a substantially horizontal direction and having a refrigerant inlet and a refrigerant outlet, means for connecting the refrigerant outlet of said first named refrigerant duct with the refrigerant inlet of said second named refrigerant duct, a header or manifold passage extending in a direction substantially parallel to said refrigerant ducts along the bottom wall of said chamber, means for connecting the refrigerant outlet of said second named refrigerant duct with said header or manifold passage, a second header or manifold passage extending in a direction substantially parallel to said refrigerant ducts and to said first named header or manifold passage along one of the upright walls of said chamber, a plurality of refrigerant conveying conduits extending between and communicating with both of said headers or manifold passages, an outlet connection for said second named header or manifold passage, said refrigerant ducts, said headers or manifold passages and said refrigerant conduits being formed by and located between the sheet metal portions of the chamber walls, and said ducts together with the connecting means therebetween, said headers or manifold passages together with the means connecting the first named header or manifold passage with said last named duct and said conduits being arranged to provide a refrigerant flow circuit through said evaporator including an extended portion in series with said inlet connection to said first named duct and another extended portion comprising said conduits connected in parallel circuit relation with each other by said headers or manifold passages and communicating with the outlet connection of said second named header or manifold passage, said connecting means between said second named refrigerant duct and said first named header or manifold passage comprising a refrigerated shelf or shelves disposed within said freezing chamber for receiving and supporting thereon a receptacle adapted to contain a substance to be congealed or frozen.

RALPH K. MILLER.
